FIG. 1

FIG. 2

FIG. 3

FIG. 4

FIG. 5

FIG. 6

FIG. 7

FIG. 8

FIG. 9

FIG. 1 is a top perspective view of an egg tray or the like showing my new design;

FIG. 2 is an enlarged fragmentary top perspective view;

FIG. 3 is a top plan view showing one-half of the egg tray, the other one-half being identical to that shown;

FIG. 4 is a side elevational view;

FIG. 5 is an end elevational view;

FIG. 6 is a fragmentary top plan view showing another embodiment of my new design which is identical to the embodiment of FIGS. 1 through 5 except for the absence of openings in the bottom of the egg receiving pockets.

FIG. 7 is a side elevational view of still another embodiment of my new design which is identical to the embodiment of FIG. 6 except for the provision of rings on the bottom of the egg receiving pockets similar to those seen on the top of the pockets in the first two embodiments;

FIG. 8 is an end elevational view thereof; and FIG. 9 is a bottom plan view thereof showing one-half of the tray, the other one-half being identical to that shown.

I claim:

The ornamental design for an egg tray or the like, as shown and described.
